BLOCK PRESS

Clair I. Young, Pittsburgh, Pa., assignor to Harbison-Walker Refractories Company, Pittsburgh, Pa., a corporation of Pennsylvania

Application January 15, 1946, Serial No. 641,275

7 Claims. (Cl. 25—89)

1

This invention relates to brick or block presses, and more particularly to those for pressing bricks with recesses in their bottoms.

One of the most popular machines for pressing bricks is known in the industry as the Boyd brick press, disclosed in its original form in Patent No. 987,124. In that press a top pad is forced down into a mold to press a charge of clay into a brick. The top pad then is retracted and the bottom of the mold, which is the bottom pad, is raised to lift the brick to the top of the mold. While the bottom pad holds the brick in this position momentarily, the brick is pushed forward off the pad to a location where it can be picked up by a workman and placed on a pallet for firing. The brick pushing means is on the front of a reciprocating charging member by which a new charge of loose clay is delivered to the mold as the bottom pad descends. The charger and pushing member are retracted behind the mold before the top pad moves down into the mold again to press another brick. It will be seen that if the bottoms of the bricks are to have recesses therein extending transversely of the machine, the projection on the bottom pad which would form such recesses would prevent the molded bricks from being pushed forward off the raised pad. Consequently, the Boyd press has not been suitable for pressing bricks having recessed bottoms.

It is among the objects of this invention to provide a brick or block press of the general character just described in which blocks with recesses in their bottoms can be pressed and automatically ejected from the machine just as rapidly and satisfactorily as flat bottom blocks.

In accordance with this invention the bottom of the mold in a block press is formed from a vertically movable bottom pad that supports a charge of clay or other suitable refractory material in the mold, while a vertically reciprocable top pad above the mold is movable downwardly into it to press the charge into a block. The bottom pad has a projection on its top extending transversely of the machine or only part way across the pad, so that a recess is formed in the bottom of the block. After each pressing operation the pads are moved upwardly, the bottom pad raising the block to the top of the mold where it immediately is gripped by pickers carried by the reciprocable mold-charging member. Actu-

2

ating means, preferably in the form of a cam, is provided for moving the pickers forwardly away from the mold with the block gripped between them, but this means is so constructed and timed with the rest of the machine that the pickers grip the block but do not begin to move it until after the bottom pad has descended far enough for its recess-forming projection to clear the bottom of the block. Thus, this projection does not interfere with lateral movement of the block away from the mold. As soon as the block has been carried by the pickers to a point readily accessible to a workman and released, the pickers are returned to their original position ready to grip the next block that is raised between them. The pickers move in unison with the charging mechanism so that the mold is charged while a block is being carried away from it by the pickers.

The preferred embodiment of the invention is illustrated in the accompanying drawings in which Fig. 1 is a side view of a brick press with the pressing portion of it shown in vertical section; Fig. 2 is a fragmentary front view of the press; Fig. 3 is a plan view, partly in section, of the picker mechanism; and Fig. 4 is an enlarged side view of the gripping means shown in Fig. 1.

Referring to Figs. 1 and 2 of the drawings, a table 1 is rigidly mounted between the front portions of a pair of vertical side frames 2 of a brick press. The central portion of this table is provided with a rectangular opening 3 extending down through it to form a mold. The bottom of this mold is formed by a bottom pad 4 mounted on a vertically reciprocable plunger 6. This plunger is mounted on a cross head 7 having at its ends circular projections 8 that extend into circular openings in the lower ends of a pair of vertical side bars 9. Each of these side bars slides up and down the inner surface of the adjoining side frame between parallel guide ribs 11 projecting from the frame. The tops of these side bars are connected by a horizontal shaft 12 on which the upper end of a heavy toggle link 13 is oscillatably mounted. The lower end of this link is provided with a central recess 14 in which the bifurcated upper end of a lower toggle link 16 is disposed. The adjoining ends of these links are connected by a horizontal shaft 17 on the central portion of which the front end of a crank arm 18 is oscillatably mounted. The lower end of the lower link

carries a shaft 19 the ends of which are mounted in a cross head 21 that carries a plunger 22 on the bottom of which there is a top pad 23. This pad is aligned with the mold so that it can be moved down into the mold when the plunger is moved downwardly.

In order to reciprocate the plungers in unison and also toward and away from each other, the rear end of crank arm 18 is shown in Fig. 1 as being journaled on the offset central portion of a crank shaft 26 the ends of which are mounted in bearings 27 in the side frames of the machine. One end of the crank shaft projects from the outside of one of the side frames and carries a large gear 28 that is driven by a pinion 29 on one end of a shaft 31 below it. This shaft likewise is journaled in both side frames, and its opposite end carries a gear 32 that is driven by a pinion 33 mounted on a shaft 34 behind it. This rear shaft is journaled in the side frames of the machine from one of which it projects and carries a pulley 35 that is driven by a belt from an electric motor (not shown). Consequently, the motor, through the pulley and the train of gears and pinions just described, continuously rotates the crank shaft. As the rear end of the crank arm is carried around the circle the front end of the arm alternately breaks and straightens the toggle and also moves the toggle, the plungers and the side bars 9 up and down in unison. The exact movement desired is obtained by mounting a roller 36 between the side frames where it is engaged by the bottom of the crank arm at certain points in the cycle.

In order to charge the mold with clay or other refractory material, all of which is referred to herein as clay, the usual reciprocating charging box 37 is mounted on the table behind the mold and directly beneath a hopper 38 that contains the loose clay. This box is reciprocated by a rod 39 connected to its rear end. The rear end of this rod is pivotally connected to the lower end of an arm 41 the upper end of which is rockably mounted on a horizontal shaft 42 mounted in the side frames. The arm is rocked by a link 43 that is pivotally connected to it and to the lower end of a lever 44 that straddles rod 39. The upper end of this lever is rigidly mounted on the central portion of a horizontal rock shaft 46 journaled in the side frames. The lower end of another lever 47 is rigidly mounted on a projecting end of the rock shaft, and the upper end of this lever carries a cam follower roller 48 that travels in the groove of a cam 49 mounted on the inside of the large gear 28. As the gear revolves, the cam rocks lever 47 and thereby, through lever 44 and link 43 and arm 41, reciprocates rod 39 and the charging box attached to it in timed relation with the movements of the plungers 6 and 22 which also are operated from gear 28.

Projecting forward from opposite sides of charging box 37 are bars 51 which, as shown in Figs. 2 and 3, carry rails 52 that travel on grooved rollers 53 attached to the side frame. Mounted on the front ends of these bars are socket members 54 in which horizontal pins 56 are removably disposed. The inner ends of these pins normally project through small perforated plates 57 welded in the ends of a horizontal angle bar 58, whereby the bar can be rocked on the pins. Connected to the inside of the flanges of the angle bar by means of cap screws 59 are a pair of blocks 60 from each of which a picker arm 61 projects rearwardly. Each arm, as shown in Fig. 1, has an upper portion and a lower por-

tion. The upper portions are supported by a cross bar 62 that has its ends mounted on lifters 63 the rear ends of which are pivotally connected to the side bars. The front ends of the lifters 63 rest on pistons 64 (Fig. 1) mounted in vertical cylinders 66 supported by the side bars. These cylinders are connected by pipes 67 to a flexible hose 68 that leads to a valve 69 connected to a compressed air supply pipe 71. This valve has an actuating stem 72 that is operated by a cam 73 on the projecting end of crank shaft 26. When this valve is opened, compressed air raises pistons 64 in cylinders 66 and thereby causes lifters 63 to raise cross bar 62 which in turn lifts the picker arms slightly for a purpose to be described presently.

As shown in Fig. 3, the lower portions of the picker arms contain small transversely extending cylinders in which pistons 76 are mounted that press against gripper plates 77 supported by the arms in such a way that the pistons can move them outwardly and springs 78 can move them back when the pressure in the cylinders is released. These cylinders are connected by pipes 79 to a flexible hose 81 that leads to a valve 82 connected to compressed air pipe 71. The actuating stem 83 for this valve likewise is operated by cam 73. The position of this cam on the crank shaft is such that when a block is ejected from the mold the cam first opens valve 82 to cause gripper plates 77 on the picker arms to move in to grip the block between them, and then the picker arms are lifted slightly by pistons 64 and held in that position until they have been moved to their forward position, whereby the block is not dragged across the table and damaged.

It is a feature of this invention that this machine can operate in the general manner of Boyd brick presses even though the bottom pad has a projection 85 on top that forms a recess in the bottom of the block and that would prevent the block from being moved forward off the bottom pad when the pad is in its uppermost position. Accordingly, after the pickers have gripped the block that has been raised to the top of the mold by the bottom pad, the forward movement of the pickers with the block is delayed until after the bottom pad has descended far enough into the mold for its projection 85 to clear the bottom of the block. This descent of the bottom pad occurs only a few moments after the pad reaches its highest point, because crank shaft 26 which causes the movements of the plungers 6 and 22 is rotating continuously and therefore the position of crank arm 18 is changing continuously. There are several ways to prevent the charging box and the picker mechanism from moving ahead the moment a block is ejected from the mold, but the preferred way of delaying forward movement of the block is to form cam 49 on the large gear in such a shape that the cam follower roller 48 will not start to move outwardly away from the axis of the cam shaft until after projection 85 on the bottom pad has dropped below the block. As soon as this happens the cam quickly throws the roller outwardly and thereby swings the lower ends of lever 44 and arm 41 forward which moves the charging box 37 and the pickers forward with the block. The valve-controlling cam 73 then leaves stem 83 to permit the air pressure behind picker pistons 76 to be released so that the block will be dropped onto a pallet 86, only about one-eighth inch below. Then the same cam leaves the other valve

stem 72 and the picker arms swing down to their original position. Immediately thereafter the large cam 49 starts to swing the cam follower roller 48 back toward the cam shaft, and the charger and the pickers are thereby drawn back to their starting positions ready to grip a new block and to reload the mold. It will be seen in Fig. 1 that the portion of cam track 49 in which roller 48 travels during the pressing of the block and until the projection 85 on the bottom pad has descended below the pressed block, is concentric with cam shaft 26. The rest of the cam is shaped to move the cam follower roller quickly away from and back towards the cam shaft.

A brick press constructed in accordance with this invention can make not only ordinary flat bottom bricks, but also those requiring recesses in their bottoms. Such recessed bricks are automatically removed from the mold to a pallet in front of it without injury to the bricks. The capacity of the machine is just as great when pressing recessed bricks as when molding plain bricks.

According to the provisions of the patent statutes, I have explained the principle and construction of my invention and have illustrated and described what I now consider to represent its best embodiment. However, I desire to have it understood that, within the scope of the appended claims, the invention may be practiced otherwise than as specifically illustrated and described.

I claim:

1. A block press comprising a mold, a bottom pad in the mold for supporting a charge of clay, a vertically reciprocable top pad movable downwardly into the mold to press said clay into a block, said bottom pad having a projection on its top to form a recess in the bottom of the block, vertically reciprocable means for periodically elevating the bottom pad to raise the block to the top of the mold, laterally movable grippers for gripping the raised block and carrying it forward away from the mold, and reciprocable means operatively connected to said grippers for reciprocating them horizontally but movable forward only after the bottom pad descends far enough for said projection to clear the bottom of the block.

2. A block press comprising a mold, a bottom pad in the mold for supporting a charge of clay, a vertically reciprocable top pad movable downwardly into the mold to press said clay into a block, said bottom pad having a projection on its top to form a recess in the bottom of the block, means for periodically elevating the bottom pad to raise the block to the top of the mold, means for gripping the raised block, and a cam synchronized with said elevated means for reciprocating said gripping means horizontally to carry the block forward away from the mold, said cam being shaped to retain said gripping means stationary above the mold until after the bottom pad descends far enough for said projection to clear the bottom of the block.

3. A block press comprising a mold, a bottom pad in the mold for supporting a charge of clay, a vertically reciprocable top pad movable downwardly into the mold to press said clay into a block, said bottom pad having a projection on its top to form a recess in the bottom of the block, vertically reciprocable means for periodically elevating the bottom pad to raise the block to the top of the mold, horizontally reciprocable means for gripping the raised block and carry-

ing it forward away from the mold, means for raising said gripping means a short distance after the block has been gripped, means for delaying said block-carrying movement of said gripping means until after the bottom pad descends far enough for said projection to clear the bottom of the block, and continuously rotating means synchronizing said vertically reciprocable means and said delaying means.

19. 4. A block press comprising a mold, a bottom pad in the mold for supporting a charge of clay, a vertically reciprocable top pad movable downwardly into the mold to press said clay into a block, said bottom pad having a projection on

15 its top to form a recess in the bottom of the block, vertically reciprocable means for periodically elevating the bottom pad to raise the block to the top of the mold, means for gripping the raised block, and means operatively connected to said pad-elevating means for starting to move said block-gripping means forward away from the mold after the bottom pad has descended far enough for said projection to clear the bottom of the block.

20. 5. A block press comprising a mold, a bottom pad in the mold for supporting a charge of clay, a vertically reciprocable top pad movable downwardly into the mold to press said clay into a block, said bottom pad having a projection on its

30 top to form a recess in the bottom of the block, continuously operating means for periodically elevating the bottom pad to raise the block to the top of the mold, means for gripping the raised block, and a cam operated by said continuously

35 operating means for reciprocating said gripping means horizontally to carry the block forward away from the mold, said cam being shaped to retain said gripping means stationary above the mold until after the bottom pad descends far enough for said projection to clear the bottom of the block.

40. 6. A block press comprising a mold, a bottom pad in the mold for supporting a charge of clay, a vertically reciprocable top pad movable downwardly into the mold to press said clay into a block, said bottom pad having a projection on its

45 top to form a recess in the bottom of the block, a continuously rotating crank shaft, mechanism operatively connecting said shaft to the bottom

50 pad for periodically elevating that pad to raise the block to the top of the mold, gripping members disposed at opposite sides of the top of the mold, fluid pressure operated means operated when the bottom pad is in its highest position

55 for moving said members inwardly to grip for a predetermined interval the block raised between them, and a cam rotating with said shaft for reciprocating said gripping members horizontally to carry the block forward away from the mold, said

60 cam being shaped to retain said gripping members and gripped block above the mold until after the bottom pad descends far enough for said projection to clear the bottom of the block.

7. A block press comprising a mold, a bottom pad in the mold for supporting a charge of clay, a vertically reciprocable top pad movable downwardly into the mold to press said clay into a block, said bottom pad having a projection on its

70 top to form a recess in the bottom of the block, vertically reciprocable means connected to the bottom pad for periodically elevating it to raise the block to the top of the mold, gripping members disposed at opposite sides of the top of the mold, continuously rotating means for actuating

75 said reciprocable means and for periodically mov-

ing said gripping members inwardly to grip for a predetermined interval the block raised between them by the bottom pad, and a cam driven by said rotating means for reciprocating said gripping members horizontally to carry the block forward away from the mold, said cam being shaped to retain said gripping members and gripped block above the mold until after the bottom pad descends far enough for said projection to clear the bottom of the block.
